UNITED STATES PATENT OFFICE.

WILLIAM E. RIDER, OF MANSFIELD, MASSACHUSETTS.

GRATE.

1,193,822.

Specification of Letters Patent. Patented Aug. 8, 1916.

Application filed November 22, 1909. Serial No. 529,239.

To all whom it may concern:

Be it known that I, WILLIAM E. RIDER, of Mansfield, in the county of Bristol and State of Massachusetts, have invented a new and 5 useful Improvement in Grates, of which the following is a specification.

My invention relates primarily to shaking grates and my main object is to increase the efficiency of the grate both by saving coal 10 and by increasing the combustion of coal actually used.

Another object is to improve the construction in such manner that the grate will be stronger and will require less repairs than 15 heretofore.

My invention accomplishes these objects and consists primarily in providing two fuel-supporting sections of the grate, one of which can move independently of the other 20 so that when the user desires to shake the movable section the fuel on the other section will be undisturbed.

A feature of my invention in its preferred form is a single header acting to guide the 25 two sections which in the preferred form are both movable independently of each other.

Other features will be pointed out below.

In the drawings Figure 1 is a plan, partly broken away, of a grate embodying my invention; Fig. 2 is an elevation of the same; 30 Fig. 3 is a section on line 3—3 of Fig. 1; Fig. 4 is a partial vertical section on line 4—4 of Fig. 1 but showing also the ash-pit doorway; Fig. 5 is a detail of the ball bearing; 35 and Fig. 6 is a detail of the operating mechanism; and Fig. 7 is a sectional detail of one end of one of the cross-pieces.

Hangers A A' are supported in any suitable way as, for example, by brackets such 40 as a in Fig. 4. The hangers are slotted to receive headers B B', cross pieces D D' D² D³, rocker arms E E' and the central header F.

The headers B B' are of well-known construction.

The cross pieces D D' D² D³ are slotted at 45 intervals, the side walls d' d' of the slots sloping upwardly and outwardly. The bottoms d d of the slots are narrower than the rest of the cross piece. Projections d² d² ex-

tend from each side of the cross pieces at the slotted portions so that the tops of the projections and the bottom of the slot form a continuous track for the ball d³. At the end of each projection is a stop d⁴. It will be noticed that by making the width of the track considerably less than the space between the side walls of the slot in the cross piece and by making the bottom of the slot of smaller dimension than the thickness of the cross piece I provide a track which is efficient to receive the ball and which is also easily kept clear of ashes and the like, the latter being true because of the clear spaces on both sides of the track, as the only limitation on the amount of such space is that the ball may not fall from the track.

The side walls d' d' of the slots in the cross pieces act not only as guides and retainers of the ball but as guides for the reciprocating grate bars as will be described below and this double guiding function is an important feature of my invention.

At one side of header F, which is preferably held rigidly in its slot in the hanger, 75 is fuel-supporting section G and at the other side is fuel-supporting section G'. Each section comprises a plurality of grate bars H mounted side by side, adjacent grate bars being adapted to move in opposite directions by means of rockers E E'. Each grate bar has the usual teeth and a substantially vertical web h, which is guided by the side walls of the slots in the cross pieces, the grate bars of section G being guided in the 80 slots in cross pieces D D' and the bars of section G' being guided in the slots in cross pieces D² D³, the two sections being independently movable as will now be explained.

At the rear of the ash pit doorway depend 85 brackets K K'. To bracket K is pivoted arm k having a rectangular slot k'. Link k⁵ is pivoted to arm k and to rock arm E' so that when shaker rod L is inserted in slot k' and moved up and down the arm k 90 and consequently rocker E' will be moved to reciprocate the bars of section G'.

Pivoted to bracket K' is arm k³ slotted at k⁴. Link k² is pivoted to arm k⁵ and to rocker E and by the use of a shaker rod in- 100

serted in slot k^4 as above described rocker E will be moved to reciprocate the bars of section G.

The single header F has projections f at one side to guide the grate bars of section B' and projections f' at the other side to guide the bars of section G.

In using my grate the shaker rod is applied to the desired arm k or k^3 in order to reciprocate the desired section of the grate. It is manifest that if both sections are desired to be shaken at once, two shaker rods may be used and both sections shaken at the same time. If, however, it is desired to 10 accumulate the fuel on the front section of the grate, this may be done and then the rear section shaken until it is thoroughly cleaned of clinkers and ashes. The fuel may be then pushed back on the rear section and the 20 front section shaken by means of its shaking mechanism. Or it may be desired to shake one section of the grate leaving the other section undisturbed and this may be readily accomplished by using the appropriate moving 25 mechanism as it will be clear that each section may be moved independently of the other section. Each grate bar reciprocates in the vertical plane of its web and is partially guided by the walls of the slot in the 30 cross piece, each section moving as a whole horizontally, and adjacent grate bars of each section being moved in opposite directions by the oscillation of the rocker for that section. While the grate bars are being reciprocated the rollers will reciprocate in their 35 bearings and by reason of the spaces between the cross pieces and the stops will remove by their reciprocation whatever ashes may accumulate in the bearings. The remainder 40 of the operation will be clear from the description.

In the use of grates it is clear that one of the most important considerations is the saving of coal and this I accomplish in several 45 ways one of which is that if one section becomes clogged, I may shake that section without shaking the other so that no coal drops from the section which is not clogged. My grate also saves coal because the latter 50 may be collected on one section while the ashes and clinkers are being shaken from the other, so that the good coal is not shaken through the grate and wasted. Moreover, the section from which the good fuel has 55 been removed may be more thoroughly shaken and cleaned out than heretofore with the result that when the good fuel has been replaced there will be thorough and complete combustion.

60 An important advantage of my grate is that the bars will support more fuel because they are better supported than heretofore and therefore stronger and moreover the likelihood of warping of the grate bars is

very much decreased with the result that the 65 bars not only retain their strength but prevent the coal falling between them with consequent waste. It will also be clear that the cost of repairs is very much less with my 70 grate for the reason that if a portion of any grate bar becomes defective it is only necessary to replace that one which extends only half the length of the grate whereas heretofore a defect required replacement by a 75 bar which was of the full length of the grate. Another advantage is that a short bar may be used for complete cleaning of the front section of the grate.

I do not claim the roller bearing as such in this application as I intend to make it the 80 subject of a separate application.

What I claim is:

1. In a grate the combination of slotted hangers; two sections supported by the hangers, one section being movable independently of the other; a substantially fixed header located between the two sections and supported in the slots in the hangers to guide the movable section; and means to move the 90 movable section.

2. In a grate the combination of two fuel-supporting sections, one movable independently of the other; bearings for said sections; hangers to support the bearings and being slotted between the bearings; a substantially fixed header located between the two sections and supported in said slots of the hangers to guide the movable section, and means to move the 95 movable section.

3. In a grate the combination of two fuel-supporting sections, each movable independently of the other; bearings for said sections; hangers to support the bearings and being slotted between the bearings; a substantially fixed header located between the two sections and supported in said slots of the hangers to guide the movable sections; and means to move the sections independently of each other. 100

4. In a grate the combination of slotted hangers, two sections supported by the hangers, one section being movable independently of the other; a substantially fixed header located between the two sections and supported in the slots in the hangers to 110 guide the movable section so as to prevent lateral movement thereof; and means to move the movable section.

5. In a grate the combination of two fuel-supporting sections, one movable independently of the other; bearings for said sections; hangers to support the bearings and being slotted between the bearings; a substantially fixed header located between the two sections, supported in said slots of the 120 hangers and guiding the movable section so as to prevent lateral movement thereof; and means to move the movable section. 125

6. In a grate the combination of two fuel-supporting sections, each movable independently of the other; bearings for said sections; hangers to support the bearings and being slotted between the bearings; a substantially fixed header located between the two sections, supported in said slots of the

hangers and guiding the movable section so as to prevent lateral movement thereof; and means to move the movable section.

WILLIAM E. RIDER.
